UNITED STATES PATENT OFFICE.

GEORGE SWEET, OF DANSVILLE, NEW YORK.

IMPROVEMENT IN WHEELWRIGHT-MACHINES.

Specification forming part of Letters Patent No. **140,094**, dated June 17, 1873; application filed May 21, 1872.

To all whom it may concern:

Be it known that I, GEORGE SWEET, of Dansville, in the county of Livingston, and in the State of New York, have invented certain new and useful Improvements in Wheelwright-Machines; and do hereby declare that the following is a full, clear, and exact description thereof, reference being had to the accompanying drawings, and to the letters of reference marked thereon, making a part of this specification.

The nature of my invention consists in the construction and arrangement of a machine for fitting fellies for wheels, as will be herein-after more fully set forth.

In order to enable others skilled in the art to which my invention appertains to make and use the same, I will now proceed to describe its construction and operation, referring to the annexed drawing, in which

Figure 1 is a plan view, and Fig. 2 a side elevation of my machine.

A represents an L-shaped frame, of any suitable dimensions, and supported upon legs or other convenient supports. Upon the frame A, at the angle, is pivoted a dial-plate, B, provided at its outer edge with notches *x x*, at equal distances apart, and corresponding in number with the number of spokes in the wheel. To this dial-plate B are bolted arms *c c*, corresponding with the number of spokes required, and these arms are connected near their outer ends by a circle D. On the under side of each arm *c*, at the outer end, is a bar, *a*, sliding in guides *b b*, and provided at its outer end with upward-projecting teeth *i i*. This bar is operated by means of a cam-lever, E, the whole forming a clamp for holding the rim or felly to be fitted to the ends of the arms *C C*. On one end of the frame A is a

sliding carriage, G, moved back and forth by a lever, H, and carrying longitudinally a revolving arbor, *d*, with auger *e* for boring the felly for the spokes. On the other end of the frame A is another sliding carriage, G', moved back and forth by a lever, H', and carrying transversely a revolving arbor, *d'*, with circular saw I, for sawing off the rim. The revolving-dial B is held at the proper points for the auger *e* to bore the holes for the spokes by means of an elbow-lever, J, pivoted to the frame, and provided with a tooth, *y*, which is thrown into the notches *x* successively by means of a spring, *f*, operating on the other end of the lever.

Having thus fully described my invention what I claim as new, and desire to secure by Letters Patent, is—

1. The sliding bar *a*, with teeth *i i*, sliding in the guides *b b* on the arm *c*, and operated by means of the cam-lever E, substantially as and for the purposes herein set forth.

2. The elbow-lever J, with point *y* and spring *f*, operating in combination with the notched dial B, substantially as and for the purposes herein set forth.

3. The combination, with the dial B, its arms *C* and circle D, and its toothed sliding bars *a* operated by the cam-levers E, of the sliding saw and auger carriages G G', all mounted upon the L-shaped frame A, and operated substantially as set forth.

In testimony that I claim the foregoing I have hereunto set my hand this 21st day of February, 1873.

GEORGE SWEET.
